CLAIM

The ornamental design for a display screen with a transitional
graphical user interface for photo album, as shown
and described.

DESCRIPTION

FIG. 1 is a front view of a first image in a sequence for a
display screen with a transitional graphical user interface for
a photo album showing our new design;

FIG. 2 is a front view of the second image thereof; and,
FIG. 3 is a front view of the third image thereof.

The broken line showing the display screen and the
remainder of the graphical user interface forms no part of the
claimed design.

The subject matter of this patent includes a process or period
in which a transitional image sequentially transitions into
another image. This process or period forms no part of the
claimed design. The appearance of the transitional image
transitions sequentially between the images shown in FIGS.
1, 2, and 3.

While the disclosed subject matter has been described in
conjunction with a number of example sequential image
transition implementations, Applicants intend to embrace
many alternative sequential image transition implementa-
tions that are within the spirit and scope of the disclosed
subject matter.
